LUFTFAHRZENGBAU SCHÜTTE-LANZ, OF MANNHEIM-RHEINAU, GERMANY.

RADIATOR ARRANGEMENT FOR AERIAL VESSELS.

Application filed September 28, 1920. Serial No. 413,443.

To all whom it may concern:

Be it known that I, KARL FRIEDRICH KAPPES, a citizen of the German Republic, and resident of Mannheim, Germany, have 5 invented a certain new and useful Radiator Arrangement for Aerial Vessels, of which the following is a specification.

The cooling-effect of radiators employed for re-cooling the cooling-water of the 10 motors of airships and flying-machines is advantageously regulated by letting the radiator more or less project out of the car. Supporting and guiding the radiator is effected by means of special frames which are attached to the outer surface of the car and which, if the car is flexibly suspended, are hinged to it so that in the case of hard landing, that is to say, if the car contacts with the ground, the radiator-frame cannot get 15 between the car and the ship-body and imperil this latter. Conducting the hot water to the radiator and the cooled water away from it can be effected, with arrangements of the before-mentioned kind and in a manner guaranteeing reliability of service, only 20 by means of hoses of a length appropriate to the extent of the movement of the radiator. But as this latter is located above the motor, the water-connections in question require 25 much space. If the radiator is in its deepest position within the car, no steam- or air-spaces must arise at the highest parts of said connections in inclined positions of the air-ship because then the proper circulation 30 of the cooling-water would be interrupted. This demand restricts and renders difficult the adaptability of radiator-arrangements of the kind in question.

The before-mentioned drawbacks are overcome 35 by my invention which consists in the facts, that, first, the radiator-frame which is arranged at the car-hood is firmly connected with the radiator; second, both the radiator and its frame can be lowered down 40 into the interior of the car, and third, the radiator is guided in its vertical motion by tubes which at the same time are employed for conducting the hot water to the radiator and the cooled water away from it, as is all 45 more fully described hereinafter.

In order to make my invention more clear, I refer to the accompanying drawings, in which—

Figure 1 is a vertical cross-section 50 through the car of an airship provided with

an arrangement according to my invention; Figure 2 is a vertical longitudinal section through the same car, of which one end is broken away, and Figure 3 is a representation similar to Figure 1, the car, however, being left away and the parts shown representing a modified form of execution.

In the form of construction shown in Figures 1 and 2, the radiator *a* is firmly connected with the frame *b* and is guided at 65 the points *c* and *d* of the car-hood. Further means for holding and guiding the radiator are provided in the interior of the car and consists of two pipes *e* and *f* (Figure 1) which support the radiator, and of the vertically upwards extending ends of two pipes *k* and *l* (Figure 2) which guide the pipes *e* and *f*. *g* and *h* (Figure 1) are stuffing boxes provided at the ends of the pipes *k* and *l*. The pipes *k* and *e* serve for leading the water 70 to be cooled to the radiator, and the pipes *f* and *l* serve for leading the cooled water away from the radiator, or reversely, and the pipes *e* and *f* with the radiator may be vertically displaced, i. e., adjusted, in the 75 pipes *k* and *l* with their stuffing-boxes *g* and *h*. The pipes *e* and *f* form parts of the radiator-supporting frame and these frame-parts are, thus, moved up or down together with the radiator itself. The air-resistance 80 during a voyage is thus reduced to a minimum, there being no radiator frame-parts projecting over the car-hood, and as no means for turning the radiator-frame up or down are necessary in the novel form of construction before-described, the weight is considerably 85 reduced and the whole is greatly simplified.

Owing to the arrangement that parts of the supporting frame of the radiator are 90 made use of for supplying the water to this latter and conduct it away from it, and that those parts, i. e., the tubes *e* and *f*, are, as such, rigid parts which are vertically displaceable in rigid parts, i. e., in the ends of 95 the pipes *k* and *l*, no flexible tubes, or no hoses respectively, need be employed. The whole can be more easily surveyed and is better accessible. Finally, as the cooling-water pipes 100 lie below the platform of the car, there is no danger of the water-circulation failing or of steam or air collecting in them.

In the form of construction shown in Figure 3, there are co-axial tubes *m* and *n*, of which the one serves for conducting the hot 110

water to the radiator and the other for leading the cooled water away from it. In this instance only one stuffing-box is required. The saving in space is in this case still 5 greater than in the first-described example.

The same combination and arrangement of parts may be employed also for the cars or hulls of big flying-machines.

Having now described my invention, what 10 I desire to secure by a patent of the United States is:

1. In an aerial vehicle, the combination with a vertically movable radiator for re-cooling the hot cooling water of the motor, 15 of telescopically arranged pipes located below the radiator; the movable parts of said pipes being connected with the said radiator and the stationary parts of the said pipes being connected with the connecting-pipes 20 between the radiator and the motor-cylinder, for the purpose set forth.

2. In an aerial vehicle, the combination with a vertically movable radiator for re-cooling the hot cooling water of the motor, 25 of two telescopically arranged pipes arranged below the radiator, the movable in-

ner pipes being connected with the radiator and being adapted the one for supplying the hot water to the radiator, the other for leading the cooled water out of it, and the 30 outer parts being connected with the connecting-pipes between the radiator and the motor-cylinder, for the purpose set forth.

3. In an aerial vehicle, the combination, with a vertically movable radiator for re-cooling the hot cooling water of the motor, 35 of telescopically arranged pipes located below the radiator; the movable parts of said pipes being connected with the said radiator and the stationary parts of the said pipes 40 being connected with the connecting-pipes between the radiator and the motor-cylinder, stationary radiator guide-parts attached to the car-hood, and movable guide-parts attached to the radiator, substantially and for 45 the purpose described.

In testimony whereof I affix my signature in presence of two witnesses.

KARL FRIEDRICH KAPPES.
